UNITED STATES PATENT OFFICE.

DAVE KAPUCZIN, OF LOS ANGELES, CALIFORNIA.

PUMP ATTACHMENT.

Application filed June 15, 1926. Serial No. 116,071.

This invention has to do with a pump attachment and it is an object of the invention to provide a pump attachment operable to feed fluid to the pump.

5 It is necessary in various situations to pump heavy or thick fluids such as heavy oils, molasses, etc. In practice difficulty is experienced in obtaining proper feed of such liquids to a pump. Further, in practice it has been found advantageous to use 10 rotary pumps for handling this general class of fluid.

It is an object of my present invention to provide a pump attachment operable to 15 feed the fluid to the pump.

It is a further object of this invention to provide a pump feed device of a design and construction whereby it is readily applicable to the standard type of pump commonly employed to handle heavy or thick 20 fluids.

It is another object of this invention to provide a feed device for a rotary pump which is operable from the pump and which 25 is operable to feed the fluid uniformly to the pump.

The various objects and features of my present invention will be best and more fully understood from the following detailed description of a typical preferred form and application of the invention throughout which description reference is had to the accompanying drawings, in which:

35 Fig. 1 is a plan view of a typical rotary pump showing the feeding attachment provided by this invention in operating position in connection therewith;

Fig. 2 is a view taken as indicated by 40 line 2—2 on Fig. 1;

Fig. 3 is an enlarged detail section taken as indicated by line 3—3 on Fig. 2;

Fig. 4 is an enlarged detail section taken as indicated by line 4—4 on Fig. 2; and

45 Fig. 5 is a sectional view of the pump.

The device which is the subject of this invention is particularly applicable to rotary pumps or dispensing devices. For example, it may be advantageously applied to 50 pumps of the general class or type set forth in my co-pending application entitled Device for dispensing fluids, filed March 5, 1925, Serial No. 13,128. In the drawings I have illustrated a simple and typical form 55 of rotary pump 10 operatively connected

with a motor 11. The pump includes, generally, a more or less cylindrical shaped casing 12 closed at both sides or ends by end plates 14, a shaft 15 extending through the casing and supported in bosses provided on 60 the outer sides of the end plates. The casing 12 is provided with a projection 17 having an opening 19 through which the fluid is admitted into the pump and with a projection 18 with an opening through which 65 the fluid discharges from the pump. In the particular pump illustrated in the drawings the projections 17 and 18 are tangentially disposed with reference to the body. A rotor 12^a is mounted in the casing on the 70 shaft and carries a plurality of blades 12^b which operate to carry the fluid through the casing from the intake opening to the discharge. It is to be understood that my present invention is not concerned with or 75 limited to any particular form or type of fluid handling means in the pump construction.

The device provided by this invention is particularly suited for construction as an 80 attachment to be applied to a pump such as I have above described. I have illustrated the device as an attachment for the pump 12 and have shown a form of construction particularly suited for this particular embodiment of the invention. The device as shown in the drawings includes, generally, a body 20, a fitting 21 for connecting the body 20 with the intake of the pump, and an impeller 22 operating in the 85 body. To apply the device to the pump 12 the boss 16 on the end plate 14 at the side of the pump opposite the motor 11 is screw threaded to receive the body 20, and the pump is provided with a shaft 15 which 90 will extend from said screw threaded boss into the body 20 to carry the impeller 22. The main part 25 of the body is in the form of a tube and is located so that the shaft 15 of the pump projects or extends centrally into or through it.

The impeller is in the form of a screw 105 mounted on the shaft 15 within the main part of the body to receive fluid at the outer or intake end of the body and feed it to the inner or discharge end of the body. The body has a tubular discharge part 26 extending from the inner end of the main part 25 at right angles to the main part of the body 110 to carry or conduct the fluid fed to the inner

end of the body. The fluid to be handled may be conducted to the intake end of the body 25 in any suitable manner, for instance through a pipe 30 provided with a suitable 5 control valve 31.

The fitting 21 is provided to connect the part 26 of the body 20 with the projection 17 of the pump to conduct fluid from the body 20 to the intake of the pump. The 10 body 20 is applied to the screw threaded boss 16 so that the part 26 is parallel with the projection 17 of the pump, in which case the fitting 21 may be a simple U-shaped fitting 15 as shown in the drawings. In practice it is convenient to make flange connections between the fitting and the parts 20 and 17. In the case shown in the drawings the opening 19 in the pump projection 17 is internally screw threaded, so I find it convenient 20 to screw thread a flanged ring 35 into the projection so that it presents a flange 36 suitable for connection with a flange 37 on one end of the fitting 21. The other end of 25 the fitting is provided with a flange 37^a to connect to a flange 36^a on the part 26 of the body.

The impeller 22, as before stated, is preferably in the form of a screw, in fact in practice it is usually desirable to make it a 30 double pitched screw as shown in the drawings. The impeller is fixed on the shaft 15 as by a key 40, or the like, and is pitched so that it will feed fluid through the body 25 in the desired direction when the shaft is 35 operated to drive the pump.

In practice various means may be provided for connecting the body 20 with the pump 10, it being preferred to provide the body at its inner end with a screw threaded 40 socket or opening 42 to receive the screw threaded boss of the pump. This construction is particularly simple and practical as it is very simple to form the socket 42 in true alignment with the main part 25 of the 45 body thus causing the main part of the body to properly align with the pump shaft when the attachment is applied. From inspection of the drawings it will be apparent that the inner end of the body is completely closed 50 except for an opening 43 provided to pass the pump shaft.

In operation the impeller being fixed on the shaft 15 operates continuously during 55 operation of the pump and is effective in advancing fluid through the body 20 and fitting 21 to the intake of the pump. It will be apparent how the impeller acts to aid the action of the pump and is effective in feeding heavy or thick fluids such as are slow to

respond to the suction or intake action of 60 an ordinary pump.

From the foregoing description it will be apparent how the device provided by this invention can be easily and quickly applied to a rotary pump of typical construction. 65 Further, it will be apparent that the device is simple of construction and operation and can be made easily and at little expense.

Having described only a typical preferred form of my invention I do not wish to limit myself to the specific details set forth, but 70 wish to reserve to myself any changes or variations that may appear to those skilled in the art or fall within the scope of the following claims.

Having described my invention, I claim:

1. An attachment for a pump having a drive shaft projecting from it through an externally screw threaded boss including a body to screw thread onto the boss, an impeller to be mounted on the shaft in the body, and a fitting for connecting the body and intake 75 of the pump.

2. An attachment for a pump having a drive shaft projecting from it through an externally screw threaded boss including a tubular body to screw thread onto the boss to be coaxial with the shaft, a screw impeller to be mounted on the shaft in the body, and a fitting for connecting the body and intake 80 of the pump.

3. An attachment for a pump having a casing with an intake opening at its periphery and an externally screwthreaded projection at one side with a drive shaft projecting from it including a tubular body to be screwthreaded to the projection to be coaxial with the shaft, a screw impeller to be 85 mounted on the shaft in the body, and a fitting for connecting the outlet opening of the 90 body with the intake opening of the pump casing.

4. An attachment for a pump having a casing with an intake opening at its periphery and an externally screwthreaded projection at one side with a drive shaft projecting from it including a tubular body to be screwthreaded to the projection to be coaxial with the shaft and having lateral outlet opening, a screw impeller to be mounted 105 on the shaft in the body, and a U-shaped fitting for connecting the outlet opening of the body with the intake opening of the pump casing.

In witness that I claim the foregoing I 110 have hereunto subscribed my name this 3rd day of June, 1926.

DAVE KAPUCZIN.
